United States Patent Office

Des. 175,836
Patented Oct. 18, 1955

175,836

DESK

Edward D. Hirsch, St. Louis, Mo.

Application March 26, 1954, Serial No. 29,702

Term of patent 7 years

(Cl. D33—7)

FIG. I

FIG. 2

FIG. 3

Fig. 1 is a front perspective view of a desk embodying my new design;

Fig. 2 is an end view of the desk taken from the left of Fig. 1; and

Fig. 3 is an end view thereof taken from the right.

I claim:

The ornamental design for a desk, substantially as shown.
